[57] CLAIM

The ornamental design for a receiving/nursing blanket, as shown and described.

DESCRIPTION

FIG. 1 is a top plan view of a receiving/nursing blanket showing my new design;

FIG. 2 is a front elevational view thereof;

FIG. 3 is a rear elevational view thereof;

FIG. 4 is a right side elevational view with the left side being a mirror image thereof; and,

FIG. 5 is an environmental top plan view of the blanket in the wrapped configuration.

The broken line showing of the baby in FIG. 5 is for illustrative purposes only and forms no part of the claimed design.
